GASOLINE DISPENSER ISLAND

Hal C. Hartsell, Jr., Winston-Salem, N.C., and David D. Tompkins, Worthington, Ohio, assignors to Gilbert & Barker Manufacturing Company, New York, N.Y.

Filed July 27, 1970, Ser. No. 24,138

Term of patent 14 years

Int. Cl. D10—04

U.S. Cl. D52—2

FIG. 3

FIG. 1 is a side elevational view of a gasoline dispenser island showing our new design; the opposite side being identical;

FIG. 2 is a top plan view of FIG. 1; and

FIG. 3 is a left end elevational view of FIG. 1, the right end being a mirror image thereof.

We claim:

The ornamental design for a gasoline dispenser island, as shown and described.
